Attorney.

UNITED STATES PATENT OFFICE.

DAVID B. WOLFORD, OF NOLIN, OREGON.

WEEDER.

1,322,742.

Specification of Letters Patent. Patented Nov. 25, 1919.

Application filed February 18, 1916. Serial No. 79,121.

To all whom it may concern:

Be it known that I, DAVID B. WOLFORD, a citizen of the United States, residing at Nolin, in the county of Umatilla and State 5 of Oregon, have invented certain new and useful Improvements in Weeders, of which the following is a specification.

My invention relates to an agricultural implement and particularly to a weeder. 10 My main object is to provide a weeder of simple construction which is capable of manufacture at low cost and which will prove durable and effective in use.

Specifically, I aim to provide an implement of this type wherein the weeder proper 15 may be adjusted and maintained at different heights; one wherein a revoluble weeder may be employed which is adapted to be fastened against rotation but which is permitted to rotate under certain conditions, and to provide a weeder of such construction that it may be satisfactorily used in gang formation.

With the above and additional objects 20 such as will hereinafter appear, in view, the invention has been embodied in one preferred form as hereinafter described and illustrated in accompanying drawings wherein:

Figure 1 is a plan view of a plurality of 25 weeders, one of which is shown fragmentarily; Fig. 2 is a front elevation of the weeders of Fig. 1; Fig. 3 is a rear elevation of one of the weeders; Fig. 4 is a side elevation of one of the weeders; Fig. 5 is a cross section on the line 5—5 of Fig. 1; Fig. 6 is a perspective view of one of the auxiliary 30 weeders employed; Fig. 7 is a plan view of the abutment or trip means for the turnable weeder; Fig. 8 is a side elevation of the 35 parts of Fig. 7 and Fig. 9 is a cross sectional view on the line 9—9 of Fig. 8.

Referring specifically to the drawings, 40 wherein like numerals designate like or similar parts in the different figures, I first provide a suitable sled or truck which may be composed of runners 1 preferably having metallic runners proper at 2 to directly engage the soil, and a connecting beam 3 mounted on the runners 2 adjacent their 45 front ends and secured to the runners as by means of bolts 4.

A superposed supporting frame is generally shown at B for a weeder or the like as illustrated at C. Weeder C is turnably 50 mounted by means of a shaft 5 of suitable construction, for instance, of a section of

metallic pipe, and is journaled in side beams 6 of the frame B.

It is to be understood that the weeder C 55 may be of any approved form. However, I find it advisable to use the form illustrated and which consists of a suitable number of traction elements or wheels 7 suitably keyed to the shaft 5 and having tangential cutting blades or weeding blades 8 riveted or otherwise fastened to the traction elements 60 at 9. It will be noted that these blades are preferably sharpened to a point at 10 and that their rear edges are blunt as at 11 and are arranged to terminate at diametrically opposite points of the center of the weeder C. However, it is obvious that a greater number of blades may be provided, if desired. Weeder C is fastened against undue movement laterally of beams 6 by 65 means of collars 12 secured to the shaft 5. 70

Superposed on the beams 6 and extending at right angles thereto, are one or more beams 13 on which rest adjacent the centers thereof, and transversely thereof, short 75 beams 13' on which rest crown beams 14. Bolts 15 pass through the beams 13, 13' and 14. Beams 14 at their front ends rest upon one or more blocks 15 supported upon beam 3. 80

The frame B is capable of movement as a whole vertically relatively to the truck so as to vary the height of the weeder C. To this end, beams or runners 1 are connected to the beams 6 by adjustable bolts 16; the beam 3 and blocks 15 and beams 14 are connected by adjustable bolts 17, and runners 1, beams 6 and beams 31 are connected by adjustable bolts 18. It may be mentioned that beams 13, 13' and 14 are connected by 90 bolts 19. When bolts 16, 17 and 18 have their nuts loosened, beams 6 may be raised on the runners 1 and insert strips 20 interposed intermediate the runners 1 and beams 6. Also blocks 15 are raised relative to beam 3 and similar blocks 20 inserted between these parts, and thereafter the nuts may be tightened to rigidify the structure. 95

Normally, the weeder C is stationary, 100 being maintained in such position by the means generally illustrated at D and shown in detail in Figs. 7, 8 and 9. This means may comprise parallel plates 22 disposed intermediate the beams 14 and against the inner faces thereof, being fastened against displacement by bolts 23 and 24. Pivots 105 mounted intermediate the plates 22 and on 110

the bolt 23 is an abutment arm 25 adapted to be fastened against or in abutting relation with the bolt 24 and being normally urged into such position by means of a coil 5 spring 26 fastened to the arm 25 and to one of the beams 14 for convenience. Co-operating with the arm 25 is a latch 27 pivoted to the plates 22 by means of a bolt 28, having an angle arm 29 to directly engage 10 the abutment arm 25 and being normally urged into such position by a coil spring 30 secured to the latch and for convenience, to one of the plates 22. Latch 27 is preferably foot operable and to this 15 end is provided with a lateral foot rest or pedal 31, preferably disposed adjacent a suitable operator's seat 32 which may be mounted by a bracket 33 from the beams 14.

With the parts of mechanism D in the relation shown in the drawings, the weeder C will be held against upward turning movement by the abutment of the rear edge of the uppermost blade 10 with the element 25 which is maintained rigid and against 20 movement by bolt 24 on one side and arm 29 of latch 27 on the other side. It may be desirable, in some instances, to permit the weeder to make a half turn, as for instance, when an obstacle in the soil is encountered, 25 or trash or other material is dragged by the lowermost blade. In such an instance, the foot of the operator by engagement with pedal 31, draws the latch 27 rearwardly and out of the path of movement of abutment 30 25, particularly at arm 29 whereupon the weeder may turn, swinging arm 25 on pivot 23 as it passes same. After a blade 10 travels past the abutment 25, spring 26 restores the abutment or arm 25 to vertical 35 position, after which the operator removes his foot from engagement with latch 27 permitting spring 30 to restore arm 29 of the latch into engagement therewith as seen in Fig. 8 so that when the other blade strikes 40 arm 25 it will serve as a rigid abutment.

It is obvious that any suitable draft means may be connected to the implement.

In some instances, I may prefer to arrange the implements in a connected series or gang 50 as suggested in Figs. 1 and 2. To this end, hinge leaves or bars 34 extend laterally from ends of the truck or sled and have registering eyes receiving horizontal pivots 35 flexibly connecting the sections for vertical 55 movement. The pivotal connection enables the different implements of a gang to better accommodate usage on uneven ground.

It will be realized that in the absence of weeding means covering the path intermediate elements C of a gang of implements, such

path would remain in its original condition. In view of this fact, I provide a plurality of weeders in the form of Fig. 6, each having an angularly disposed scraping blade 36 sharpened at its scraping edge 37 and being 65 connected to the inner faces of runners 1 as by means of bolts 38 passing through the runners and through arms 39 integral with blades 36. It will be noted that the blades 36 of the auxiliary scrapers of adjoining implements overlap each other as shown in Fig. 1.

It is preferred that the scraper blades 10 and 36 project a slight distance into the soil in order to cut the weeds as the implement is 75 drawn along, at or adjacent their roots.

Since merely the preferred embodiment has been illustrated and described, it is to be understood that changes in the details of construction may be resorted to within the 80 spirit and scope of the appended claim.

I claim:

In a weeding implement, a truck adapted to directly engage the soil, a frame secured to said truck, and adapted to be moved vertically relative to said truck, a shaft rotatably mounted on said frame, a plurality of wheels secured to said shaft and adapted to engage the soil, a plurality of tangentially disposed cutting blades secured to said 90 wheels, a platform secured to the above mentioned frame; said platform comprising two spaced parallel bars; a plate secured to the inner face of each of said bars, a depending member pivotally connected to the securing means for the above mentioned plates and normally in engagement with the rear edge of one of said blades; said securing means serving as an abutting means for the above mentioned depending member, a 100 spring secured to the depending member and to the above mentioned platform and adapted to hold the depending member in abutting relation with the above mentioned securing means, an upstanding latch pivotally connected to the frame, an angle arm secured to said latch and adapted to removably engage the depending member, and a spring secured to said latch and one of the above mentioned plates and adapted to normally hold the angle arm and the upper portion of the above mentioned depending member in abutting relation.

In testimony whereof I affix my signature in presence of two witnesses.

DAVID B. WOLFORD.
